FABRICATED DERRICK.

Application filed November 10, 1925. Serial No. 68,203.

This invention relates to an improved type of fabricated derrick construction, and is particularly directed to the general class of derrick structures usually employed as 5 part of the equipment utilized in the drilling and operating of oil, gas, and like wells.

Derricks of the general character used in the oil industry comprise four upwardly converging corner posts or legs connected 10 together around the four sides of the derrick at vertically spaced intervals by transverse girts and braced by intermediate diagonal anti-vibration or sway braces.

When such derricks are constructed of 15 wood, it is the usual practice to build the derrick in its position of use, sufficient standard lumber being hauled to the field where the various parts are made and the derrick assembled piece by piece and nailed or 20 spiked together.

Derricks constructed of structural steel are usually fabricated at the factory and then shipped to the field for erection. These 25 steel derricks follow the general design of the wood derricks, their corner posts or legs each being formed of a single string of several sections of pipe or angle-iron placed end to end in longitudinal alignment and rigidly secured together at the abutting ends 30 of the sections by joint-plates and bolts or by other similar means. In view of the heavy expense connected with erection of derricks in the field, certain efforts have 35 heretofore been made to preassemble certain portions of steel derricks at the factory or at a field shop, it being the usual practice in such instances to pre-assemble certain of the parts to form sections or panels of 40 heights convenient to handle, but with the single leg type of construction now in use it is only possible to pre-assemble the parts 45 in panel form for two opposite sides of a derrick, thus providing the four legs, the braces and girts of the other two sides being subsequently filled in during erection of the derrick.

One of the major objects of the present invention is to provide a derrick construction of which the fabricated parts constituting each of the four sides of the derrick may 50 be pre-assembled in panel form prior to the erection of the derrick.

Another important object is to so construct a derrick that joint-plates are unnecessary.

A further object of importance is to arrange the panels of adjacent sides in relative break-joint relationship and with the leg members thereof in overlapping or intermeshing relation so as to form a double corner post or leg at each of the four corners 55 of the completed derrick.

Still another object is to provide a panel derrick construction in which the several panels each have an upper and a lower transverse marginal girt adapted to engage and 60 be secured to the adjacent transverse marginal girts of the vertically adjacent panels.

Another object is to provide a derrick construction of the above character in which the leg members of the panels terminate at the 65 upper and lower transverse marginal girts.

Other advantages incident to a derrick construction of the type of the present invention are: that the separate panels may be made of lighter material than usually employed in derricks now in use and of equal height and capacity; that the resulting completed structure will provide a derrick of great strength and stability; that it can be 70 erected or dismantled at a minimum field expense; that it can be erected or dismantled with less skilled workmen and with greater relative speed; and that repeated dismantling and reerection can be effected without 75 appreciable wear or injury to the parts. 80

Various other objects and advantages will be more fully apparent from the following description of the accompanying drawings which form a part of this disclosure, and which illustrate a preferred form of embodiment of the invention. 85

Of the drawings:

Fig. 1 is an elevation of a derrick constructed in accordance with the present invention.

Fig. 2 is an enlarged plan section, partly broken, taken on line 2—2 of Fig. 1.

Fig. 3 is an enlarged elevation of the lower portion of the derrick in the course of erection.

Fig. 4 is an enlarged section taken on line 4—4 of Fig. 3.

Fig. 5 is an enlarged section taken on line 5—5 of Fig. 3.

Fig. 6 is an elevation of a single panel section of which two opposite sides of the derrick are formed.

Fig. 7 is a similar elevation of one of

the panel sections of which the other two sides of the derrick are formed.

The derrick illustrated in the drawings is shown as being made of structural steel shapes, but it is to be understood that the present invention in its broad aspect is not restricted to any particular material, the specific embodiment disclosed being primarily intended for the purpose of illustrating a practical application of the principles of construction involved.

As shown, each of the four sides of the derrick is formed of a plurality of panel sections secured together in vertical alignment with the several sections of the respective sides of suitable dimensions to produce a completed derrick gradually converging or tapering upwardly to the derrick top upon which will be mounted the usual 20 crown-block.

The panel sections A of two opposite sides are of relatively similar construction and the panel sections B of the other two sides are also of relatively similar construction, 25 but slightly different from the panel sections A, therefore it will suffice herein to describe in detail one of each of the sections A and B.

Each panel section A comprises opposite 30 angle-iron leg members *a* disposed vertically at slightly converging angles corresponding to the general taper of the completed derrick, lower and upper transverse marginal girts 2 and 3, (so called because they 35 form the lower and upper margins of the panel) an intermediate transverse girt 4, a lower pair of diagonal sway braces 5 and 6, an upper pair of similar diagonal sway braces 7 and 8, and lower and upper reinforcing vertical braces 9 and 10. All of 40 these braces and girts are of angle-iron form and are swaged at opposite ends to bring both flanges thereof to parallel contact, thus providing securing ends of double 45 thickness which are bored or punched to receive securing rivets or bolts. The several girts and sway braces are positioned to engage the inner faces of the adjacent flanges of the respective leg members *a*, the horizontal flanges of the marginal girts 2 and 3 extending inwardly, the respective horizontal flanges of the intermediate girt 4 and of the sway braces 5 and 7 extending outwardly, while the respective horizontal 50 flanges of the sway braces 6 and 8 extend inwardly, the opposite ends of these girts and sway braces being secured to the respective leg members *a* preferably by bolts and nuts with the bolt heads on the inside 55 and the associated nuts tightened against the outer face of the respective leg members. These several bolts are designated by reference characters consisting of a suffix added to the numeral designating the respective 60 parts they secure to the leg members, thus 65

the bolts 2^a secure the transverse marginal girt 2 to the lower ends of the leg members *a*, the bolts 3^a secure the transverse marginal girt 3 to the upper ends of said leg members, while the bolts 4^a, 5^a, 6^a, 7^a and 8^a secure 70 the intermediate girt and the respective diagonal sway braces to said leg members. The upper end of the vertical reinforcing brace 9 is positioned between the two diagonal sway braces 5 and 6 at their point of 75 crossing and is secured to the vertical flanges of both of said sway braces by a bolt 9^a (see Fig. 5) and the lower end of said vertical brace 9 is secured against the inner face of the vertical flange of the marginal girt 2 by a bolt 9^b. The vertical brace 10 is similarly secured between and to the vertical flanges of the diagonal sway braces 7 and 8 by a bolt 10^a and to the vertical flange of the intermediate girt 4 by a bolt 10^b. 80 85

This provides a complete rigid panel unit which will hold its shape during shipping and throughout its handling during erection and dismantling as well as while assembled in the derrick structure.

Each panel section B comprises opposite angle-iron leg members *b*, lower and upper transverse marginal girts 12 and 13, an intermediate transverse girt 14, a lower pair of diagonal sway braces 15 and 16, an upper pair of diagonal sway braces 17 and 18, and lower and upper reinforcing vertical braces 19 and 20. All of these girts and braces are of the same construction as those of the panel sections A. However, their ends are secured by bolts to the outer faces of the adjacent flanges of the respective leg members *b* instead of to the inner faces as are the braces and girts of the sections A. Bolts 12^a secure the ends of the lower marginal girt 12 to the lower ends of the respective leg members *b*, bolts 13^a secure the ends of the upper marginal girt 13 to the upper ends of the respective leg members *b*, while bolts 14^a, 15^a, 16^a, 17^a and 18^a secure the intermediate girt 14 and the respective diagonal sway braces to the leg members *b*. The vertical braces 19 and 20 are positioned in the same relative positions as are the like braces of the sections A and are secured in position 110 by bolts 19^a, 19^b and bolts 20^a and 20^b. 115 120

While it is evident and is clearly realized that the derrick may, if desired, be erected piece by piece, the preferred method to be followed in practice will be to pre-assemble the various panel sections, leaving to the field crew only the work of assembling these panel sections into a completed derrick. Therefore, I will, for the purpose of this disclosure, limit the description of the erection to the manner in which the several sections are secured together to form the completed structure, it, of course, being understood that the erection will be progressive 125 from the bottom to the top of the derrick, 130

and further; that as the sections of the different sides are in break-joint relationship two of the lowermost and two of the top sections will be of different relative height than 5 the rest of the sections so that the derrick may have a level base and end with a level top.

With particular reference to Figs. 1, 3 and 4, it will be noted that each A section 10 is vertically aligned with and rests upon the next lower A section with the horizontal flanges of the marginal girts thereof in engagement. That is, the marginal girt 2 of one panel section engages the marginal girt 15 3 of the next lower section. The horizontal flanges of these coengaging marginal girts are secured together throughout their lengths by relatively spaced bolts 21, this being one of the reasons why it is not necessary 20 to provide joint-plates for the leg members.

The several panel sections B also are assembled in the same manner with each B section vertically aligned with and resting 25 upon the next lower B section and with the coengaging marginal girts 12 and 13 secured together by bolts 21^a.

While the sections A and B are secured to the companion A and B sections in the 30 same manner, it will be seen, with particular reference to Figs. 3 and 4, that the adjacent A and B sections overlap each other by one-half their respective heights, thus bringing the joints 22 between the vertically adjacent A sections in regular staggered relation to the joints 22^a between the vertically adjacent B sections, this being a further reason for the elimination of joint-plates for the leg members.

40 Referring now more particularly to Fig. 2 of the drawings, it will be noted that the panel sections A are assembled with the panel sections B so that the angle-iron leg members *a* have an intermeshing or overlapping engagement with the angle-iron leg members *b* of the panel sections B, with each leg angle engaging the heads of the several bolts which secure the several girts and braces to their respective leg members, thus 45 forming at each corner of the derrick a corner post or leg of double construction.

With the panel sections thus assembled the nested leg members are secured together at intervals by bolts A' and B', each of said 50 bolts extending through the flanges of both leg members *a* and *b* of each corner post of the derrick. These leg bolts A' and B' are preferably positioned on opposite sides of and closely adjacent to the points of 55 security of the respective girts and braces and if desired additional leg bolts may be positioned between such points as indicated in Fig. 1.

60 This preferred method of assembling the panel sections is followed throughout the

erection of the entire derrick, with a great saving in the time and expense of field erection over the usual methods now in vogue, this being of great importance in view of the fact that derrick or rig-builders are highly skilled.

It will thus be evident that all fabrication and pre-assembling which may be performed in a factory or shop with relatively cheaper labor represents a cost saving of 75 major importance.

From the above it will be seen that the present invention provides a derrick of an exceptionally strong and rigid character which will be capable of withstanding hard 80 usage, one of the most important features contributing to this superior strength and rigidity being the fact that the several panels break joint at the marginal girts and in vertically staggered relationship and that the 85 marginal girts are secured together throughout their lengths thereby producing a construction which is a great deal stronger against transverse strains than any derrick structure which is secured together only at 90 the leg joints.

It will also be evident that this invention provides a complete panel derrick which can be erected or dismantled with maximum speed and a minimum field cost and which, 95 even if constructed of wood, can be dismantled with practically no deterioration or breakage as compared with the usual types of nailed derricks.

While the specific embodiment of the invention herein illustrated and described is 100 fully capable of fulfilling all of the objects primarily stated, it is to be understood that I do not wish to limit the invention in this regard, for it is susceptible of embodiment in 105 various other forms, all coming within the scope of the following claims.

I claim as my invention:

1. In a derrick of the nature disclosed, the combination of: relatively spaced corner legs 110 each comprising a plurality of longitudinally aligned leg sections; lower transverse girts connected at opposite ends to the respective lower ends of the leg sections of adjacent legs; upper transverse girts connected 115 at opposite ends to the respective upper ends of said leg sections; and means for securing each lower girt to the vertically adjacent upper girt.

2. In a derrick of the nature disclosed, the combination of: four relatively spaced corner legs each comprising a double string of longitudinally aligned angle leg sections, one string nested within the other with their flanges in parallel relationship with the adjacent sides of the derrick; lower transverse girts disposed on opposite sides of the derrick and connected at opposite ends to the respective lower ends of the inner leg sections of the adjacent legs; upper transverse 130

girts on said opposite sides of the derrick and connected at opposite ends to the respective upper ends of said inner leg sections; other lower transverse girts disposed on the other sides of the derrick and connected at opposite ends to the respective lower ends of the outer leg sections; other upper transverse girts disposed on said other sides of the derrick and connected at opposite ends to the respective upper ends of said outer leg sections; and means for connecting each lower transverse girt to the vertically adjacent upper transverse girt.

3. In a derrick of the nature disclosed, the combination of: four relatively spaced corner legs each comprising a double string of longitudinally aligned angle leg sections, one string nested within the other with their flanges in parallel relationship with the adjacent sides of the derrick; lower transverse girts disposed on opposite sides of the derrick and connected at opposite ends to the respective lower ends of the inner leg sections of the adjacent legs; upper transverse girts on said opposite sides of the derrick and connected at opposite ends to the respective upper ends of said inner leg sections; other lower transverse girts disposed on the other sides of the derrick and connected at opposite ends to the respective lower ends of the outer leg sections; other upper transverse girts disposed on said other sides of the derrick and connected at opposite ends to the respective upper ends of said outer leg sections; and means for connecting each lower transverse girt to the vertically adjacent upper transverse girt; the inner leg sections of each corner leg being disposed in

break-joint relationship with the outer leg sections thereof. 40

4. A derrick of the nature disclosed having each of its sides formed of a plurality of vertically aligned complete pre-assembled panel sections secured to each other with each panel section provided with vertical corner leg members secured to the vertical corner leg members of the adjacent panel sections. 45

5. A derrick of the nature disclosed having each of its sides formed of complete pre-assembled panel sections with each panel section provided with transverse marginal girts secured to the transverse marginal girts of the vertically adjacent panel sections. 50

6. A derrick of the nature disclosed having each of its sides formed of complete pre-assembled panel sections having transverse marginal girts, with the several panel sections secured together at the corners of the derrick and the transverse marginal girts of each panel section secured to the transverse marginal girts of the vertically adjacent panel sections. 60

7. A derrick of the nature disclosed having each of its sides formed of complete pre-assembled panel sections, with the several panel sections secured together at the corners of the derrick and to the vertically adjacent panel sections, the panel sections of each side being disposed in break-joint relationship with those of the adjacent sides. 65

In testimony whereof, I have hereunto set my hand at Los Angeles, California, this 3rd day of November, 1925.

BURTON BLACK.
